UNITED STATES PATENT OFFICE.

ROBERT N. THOMAS, OF SHENANDOAH, IOWA.

CORN-HUSKER.

SPECIFICATION forming part of Letters Patent No. 767,918, dated August 16, 1904.

Application filed July 22, 1901. Serial No. 69,231. (No model.)

To all whom it may concern:

Be it known that I, ROBERT N. THOMAS, a citizen of the United States, and a resident of Shenandoah, in the county of Page and State 5 of Iowa, have invented certain new and useful Improvements in Corn-Huskers, of which the following is a full, clear, and exact specification.

The object of my invention is to provide a 10 twin-spurred shield conforming in shape to and adapted to be worn over the heel of the hand in such manner that the upper portion of the hand is left free to grasp and assist in manipulating the ear of corn after it is stripped of 15 the grain to break the shank off.

A further object of the invention is to so 20 construct said shield that the twin spurs thereof may be readily adjustable thereon either by being set nearer together and parallel or at 25 an angle to each other or reversed, so as to adapt it to the peculiarities of the shape of the hand and movements of the operator; and yet another object is to prevent the husks and 30 kernels of corn from getting lodged under the spurs and interfering with the perfect operation 35 of the same and so construct said spurs that the ear meets with no obstruction as it is moved over the shield until it engages said spurs. This I accomplish by the means hereinafter fully described and as particularly 40 pointed out in the claims.

In the drawings, Figure 1 illustrates a human hand, showing my invention applied thereto. Fig. 2 is a side edge view of the 45 spurred shield thereof. Fig. 3 is a lower edge view of the same. Fig. 4 is a section taken on dotted line 4-4, Fig. 1, looking in the direction indicated by the arrows.

The principal feature of my invention is 50 the peculiar spurred shield, which is worn over the heel of the palm of the hand. This shield A is preferably of an oblong shape and has three of its corners rounded just sufficiently to avoid sharp angles and has the corner nearest the little finger rounded to a much greater extent, so as not to interfere with the movements of the little finger when in use. This shield is about the relative dimensions shown in the drawings, and is bent or dished 55 so as to fit over the heel or lower portion of

the palm of the hand in such position that both the thumb and fingers are free, and it is mounted upon an L-shaped strip of leather or other suitable material which constitutes a mitt B, whose horizontal portion is secured to the wrist by means of the straps b b and whose vertical portion is secured in front of the palm of the hand by the straps c, that buckle together back of the hand, as shown in the drawings. I do not, however, desire to be 60 confined to the use of a mitt B, such as herein shown and described. Any glove or mitt could be made to answer the purpose. The shield A is preferably secured to mitt B by rivets extended through suitable openings 65 therein located at or near its corners and has removably secured to its outer exposed surface two spurs C C. These spurs are preferably made of cast-steel or stamped steel and are so made that the spurs proper are inverted- 70 L-shaped extensions of one end of a screw-plate d d, that is rigidly secured to the shield by means of screws e e, which are inserted through holes therein and tapped into but preferably not through said screw-plate. 75 The holes through which these screws pass are part of several series of holes made in said shield at suitable distances apart and in planes arranged at different angles to each other, and it is an important feature of my 80 invention that the spurs can be removed from one part of the shield and secured thereto at another point and at a different angle from that which it previously occupied by simply removing the screws e e from the holes of one 85 series and inserting them through another series and screwing them into the screw-plate of the spurs. In the drawings I have shown the shield as provided with but four of these series of holes, in two series of which the 90 spurs C are shown secured to the shield, while the two remaining series h and k are located between said spurs. It is obvious there may be any number of these series of holes and they may be located anywhere 95 therein and at such distances apart and at such angle to each other as may be desired. By my improvements one or more of said spurs may be used, and, if preferred, they may be arranged in the reverse position to 100

that shown in the drawings. One peculiarity of these spurs is that though made of a separate piece of metal from the shield the portions thereof secured to said shield present no obstruction to the movement of the ear of corn as it is advanced toward the point of the spurs. This prevents the niching or abrasion of the surface of the kernels and insures a saving of grain and a higher grade of corn than would otherwise be the case. Then, besides, by rounding the ends of the screw-plates from which the spurs project—in other words, the crotch of the spurs—I prevent the husks and kernels from crowding and lodging under said spurs. This is a difficulty now experienced which oftentimes prevents the spurs from doing effective work until after the space under the spurs has been forcibly cleared out. This feature is a valuable aid to the effective operation of said spurs.

What I claim as new is—

1. A corn-husker comprising a shield having several series of holes therein, several removable spurs, and means adapted to be passed through the holes of any of said series and secure said spurs to the exterior of said shield in planes longitudinal with or transverse to the longest diameter of said shield.
2. A corn-husker comprising a shield, and a spur consisting of an inverted-L-shaped extension of the rounded end of a screw-plate

that is removably secured to the exterior of said shield.

3. A corn-husker comprising a shield having several series of holes therein, and a spur consisting of an inverted-L-shaped extension of a screw-plate, and means for removably securing said spur to the exterior of said shield in planes intersecting the holes of any of said series.

4. A corn-husker comprising a shield having several series of holes, a spur consisting of an inverted-L-shaped extension of the rounded end of a screw-plate and means for removably and adjustably securing said spur to the exterior of said shield in planes intersecting the holes of any of said series respectively.

5. A corn-husker, comprising a dished shield having one of its corners more rounded than the others and having several series of holes therein, several spurs each consisting of an inverted-L-shaped extension of the rounded end of a screw-plate, and means for removably and adjustably securing said spurs to the exterior of said shield in planes intersecting the holes of any of said series, respectively.

ROBERT N. THOMAS.
